UNITED STATES PATENT OFFICE.

PHILIP A. MYERS, OF ASHLAND, OHIO, ASSIGNOR TO F. E. MYERS AND BROTHER, A COPARTNERSHIP CONSISTING OF FRANCIS E. MYERS AND PHILIP A. MYERS, OF ASHLAND, OHIO.

PUMP-JACK.

1,146,729.

Specification of Letters Patent. Patented July 13, 1915.

Application filed October 21, 1914. Serial No. 867,876.

To all whom it may concern:

Be it known that I, PHILIP A. MYERS, a citizen of the United States, residing at Ashland, in the county of Ashland and State of Ohio, have invented certain new and useful Improvements in Pump-Jacks, of which the following is a specification, reference being had therein to the accompanying drawing.

10 This invention relates to pump jacks, and the object of the invention is to provide a jack which can be attached to pumps of various kinds and which may be placed with the base extending about the base of the 15 pump and disconnected therefrom so that the thrust will be upon the supporting platform and not upon the pump.

A further object is to provide such a device which will be very simple in its construction, positive in its operation, and of a strong, durable character.

In the accompanying drawings Figure 1 is a perspective view of my improved pumping jack, showing the same attached to a pump; and Fig. 2 is a transverse sectional view taken just above the base, and omitting the pump.

In these drawings I have illustrated one embodiment of my invention, and have shown the same as comprising a base consisting of two separable side members 1 connected one to the other by tie rods 2 and having journaled therein a shaft 3. The forward ends of the side members project some distance beyond the shaft and tie rods, and thus enable them to extend on the opposite sides of the pump base and thereby position the shaft close to the base. To permit of this arrangement the ends of the side members 1 are preferably flared outwardly, as shown, and are recessed along their inner edges, as shown at 4, to enable them to overlap the flange of the pump base. Mounted on the shaft 3 are crank wheels 5 which are here shown in the form of gears which mesh with and are driven by pinions 6 carried by a shaft 7 on which is mounted a driving pulley 8. Connected with each crank wheel or gear 5 is a pitman or side arm 9. These 45 pitmen when in their operative position extend upward and are connected one to the other by a crosshead 10. The crosshead is preferably bolted at its ends to the side arms, and the arms may be provided with a series of holes 11 to enable the crosshead to

be adjusted relatively thereto. This crosshead is adapted for connection with a pump rod 12 which forms a part of a pump 13. It is desirable that the connection between the pump rod and the crosshead should have 60 movement about a transverse axis to permit of the operation of the pitmen, and that it should be movable about a longitudinal axis to permit the cross-head to occupy different positions relatively to the pump rod, which 65 is usually flat. To this end I have made this connection in the form of a universal joint, the crosshead being provided with a socket 14 having mounted therein a ball 15 in which is formed a longitudinal opening 70 to receive the pump rod. A pin 16 extends through the upper portion of the ball and the pump rod to separably connect the same.

The operation of the pump jack will be readily understood from the foregoing description, and it will be apparent that I have provided a jack which can be connected with pumps of various kinds because of the construction which permits it to be placed in different positions about the base of the 80 pump, thus it is applicable not only to a pump having its discharge spout on the side opposite the handle, but also to a pump having its discharge spout at right angles to the handle. Pump jacks of this type here- 85 tofore employed could not be applied to pumps having this latter arrangement because of the interference of the jack with parts of the pump. By providing a base comprising separable side members it is possible to adjust these side members to adapt the jack to pumps of different kinds. Ordinarily, this adjustment will be made at the factory, and tie rods and shafts of different lengths employed. In this way the jack 90 can be accommodated to pump bases of different sizes and different kinds without the necessity of each size constituting a separate manufacturing proposition. The base of the jack having been arranged to accommodate it to the particular pump to which it is desired to apply it, the jack may be placed about the pump base in any desired position relative to the flat pump rod, and the connecting device on the crosshead adjusted to 100 correspond to that position. Further, this connecting device is of such a character as to permit of the movement of the pitmen after the crosshead has been connected with the pump rod, regardless of the position of 110

the pump rod. Further, it will be apparent that the device is exceedingly simple in its construction, very strong and durable, and is of such a character that it can be manufactured at a relatively low cost.

While I have shown and described one embodiment of my invention, I wish it to be understood that I do not desire to be limited to the details of construction shown and described, as obvious modifications will occur to a person skilled in the art.

Having thus fully described my invention, what I claim as new and desire to secure by Letters Patent, is:

1. A pump jack comprising a base open on one side to permit it to be placed about the base of a pump, a shaft journaled on said base, crank wheels mounted on said shaft, pitmen connected to the respective 10 crank wheels, a crosshead connected to said pitmen and a connecting device comprising a universal joint to connect the crosshead to the pump rod of said pump and to permit said pump rod to move relatively to said crosshead about both a longitudinal axis and a transverse axis.

2. A pump jack comprising a base consisting of two side members separably connected to permit them to be spaced different 30 distances apart, said side members being spaced away from each other at one end of the base to permit them to extend on opposite sides of the base of a pump, crank wheels mounted on said base, pitmen connected with the respective crank wheels, a crosshead connecting said pitmen, and a connecting device comprising a universal joint to connect the crosshead to the pump rod of said pump and to permit said pump rod to move relatively to said crosshead

about both a longitudinal axis and a transverse axis.

3. A pump jack comprising a base consisting of two side members separably connected to permit them to be spaced different 45 distances apart, said side members being spaced away from each other at one end of the base to permit them to extend on opposite sides of the base of a pump, crank wheels mounted on said base, pitmen connected with the respective crank wheels, a crosshead connecting said pitmen and a connecting device to connect the crosshead to the pump rod of said pump, said connecting device comprising a socket formed in said 50 crosshead, a ball mounted in said socket and having a longitudinal opening to receive said pump rod, and means for fastening said pump rod to said ball.

4. A pump jack comprising a base consisting of separable side members, a tie rod to connect said side members, a shaft journaled in said base, said tie rod and said shaft being located at points removed from one end of said base to permit said side 60 members to extend on opposite sides of a pump base, crank wheels mounted on said shaft, pitmen connected to said crank wheels, a crosshead connecting said pitmen, and a connecting device to connect said 65 crosshead to the pump rod of said pump, said device being mounted on said crosshead for movement relative thereto about both a longitudinal axis and a transverse axis.

In testimony whereof, I affix my signature in presence of two witnesses.

PHILIP A. MYERS.
